EXHAUST PROPULSION ENGINE, INCLUDING MEANS FOR IGNITING THE FUEL WITHIN EXHAUST CHAMBERS EXTERIORLY OF THE CYLINDERS

Harold G. Myhr, Pacific Grove, Calif.

Application February 27, 1950, Serial No. 146,413

6 Claims. (Cl. 60—35.6)

1

This invention relates to a jet or exhaust propulsion engine and has for one of its objects the production of a simple and efficient means for driving a vehicle by means of the exhaust which is ignited at the point of discharge of the exhaust from the exhaust chambers or funnels of the engine.

A further object of this invention is the production of a simple and efficient arrangement of compression cylinders, exhaust chambers and control valve mechanism for discharging exhaust from the exhaust chambers of an engine to create driving power.

Other objects and advantages of the present invention will appear throughout the following specification and claims.

In the drawings:

Figure 1 is a top plan view of a four-cycle combustion and exhaust drive engine, certain parts being shown in section;

Figure 2 is a side elevational view of the engine;

Figure 3 is a longitudinal sectional view of the engine taken through one of the cylinders and the exhaust chamber or funnel carried thereby, certain parts being shown in elevation;

Figure 4 is a fragmentary horizontal sectional view taken through the exhaust chamber or funnel and compression chamber control valve of one cylinder, certain parts of the engine being shown in elevation;

Figure 5 is a longitudinal sectional view through one of the compression cylinders showing the compression intake control valve and casing in longitudinal section, certain parts of the engine being shown in elevation;

Figure 6 is an enlarged side elevational view of the valve actuating mechanism;

Figure 7 is an enlarged transverse sectional view of the inner end of the spring supporting housings for the exhaust chambers;

Figure 8 is a side elevational view of the carburetor pipe which feeds the fuel to the engine.

By referring to the drawings in detail, it will be seen that there is shown an engine of the four-cycle type having four primary cylinders 10, 11, 12 and 13 carried by an engine base 14, which base 14 is mounted upon a suitable vehicle V. A crank shaft 15 is journaled in the base upon the bearings such as the bearings 16. The crank shaft 15 is connected to the piston of the cylinders in the conventional manner and at one end to the operating motor 17 of any suitable type having a clutch 18, a generator 19, a starter motor 20, and a battery 21, shown in diagram

2

form in Figure 1. The base 14 is provided with a conventional oil pan 22 and drain plug 23.

The base 14 carries a suitable longitudinally extending cam shaft 24 carrying a pair of valve actuating cams 25 and 26 to each cylinder, for operating the valves of each cylinder. Gears 27 and 27^a shown in dotted lines in Figure 1 drive the cam shaft 24 from the crank shaft 15 to rotate the shaft 24 and to open and close the intake 10 and exhaust valves of each cylinder in proper timed relation, as is conventional with engines of this type. A casing 28 encloses the gears 27 and 27^a and supports a distributor 29 and a conventional coil 30, all of a conventional variety. A spark plug wire conduit 31 encases the ignition wires 32 leading to the spark plugs 33, 34, 35 and 36 carried by the exhaust chambers or funnels 37, 38, 39 and 40 of the cylinders 10 to 13 respectively. The conduit 31 is supported by suitable hangers 41 and 42 which are anchored at suitable points to the cylinders of the engine.

Each cylinder 10, 11, 12 and 13 is substantially similar and is constructed in detail as shown in Figures 3 to 5 of the drawings. A suitable carburetor 43 of a conventional type is connected to a fuel supply line in the usual manner and the carburetor 43 is carried by and communicates with the intake manifold 44 which leads to and communicates with the fuel intake casing 45 of each cylinder. The right-angularly disposed outlet connections 46 at the ends of the manifold 44 provide a connection with the fuel intake casings 45 of the respective cylinders 10, 11, 12 and 13. Each intake casing 45 is provided with a discharge port 47 communicating with the interior of the cylinder, near its outer end, such as the cylinder 13 shown in Figures 3, 4 and 5, for supplying fuel to the cylinder. A valve 48 is normally seated upon the valve seat 49 to prevent fuel from passing from the intake chamber 50 out through the discharge port 47. A coil spring 51 carried by the stem 52 of the valve 48 yieldably holds the valve upon its seat in the conventional manner until the stem 52 is moved longitudinally to open the valve by means of the cam 26 which is actuated by the rotation of the cam shaft 24.

The stem 52 is directly operated through the medium of the plunger 53 which is slidably mounted through the valve actuating housing 54, the housing 54 being anchored to the base 14. There is a valve actuating housing 54 for each cylinder valve mechanism. Each housing 54 supports a rocker arm 55 which is pivoted at 56 and engages at one end the reciprocating actuating

plunger 57 which is adjustably secured thereto to facilitate proper action. This plunger 57 is carried by the housing 54, as shown in Figure 6, and is slideable therethrough. This plunger 57 is actuated by the cam 25 of the shaft 24. The outer end 55 of the rocker arm 55 is adjustably connected to the end of the valve stem 58 of the exhaust discharge mechanism. A similar actuating mechanism is provided for the discharge mechanism of each cylinder.

An exhaust chamber or funnel, as previously stated, is carried by each cylinder in a manner as shown in Figure 1, and the manner in which the funnel 40 is mounted upon the cylinder 13 is shown in Figures 3, 4 and 5. Each funnel 40 is provided with an inner chamber 59 which communicates with the port 60 leading from the interior of the adjacent cylinder, such as the cylinder 13 in Figures 3 and 4. The fuel is adapted to pass from the cylinder 13 through the port 60 into the inner chamber 59. When the valve 61 which is carried by the stem 58 is withdrawn from its seat 62, the fuel will pass out through the open valve seat 62 toward the open flared end 63 of the exhaust chamber or funnel 40. The chamber or funnel 40 is provided with a hollow sleeve 64 at its inner end and a piston 65 is fixed to the stem 58. The piston 65 is slidably mounted and snugly fits into the sleeve 64 and is adapted to equalize the pressure in the chamber 59 between the valve 61 and the piston 65 and hold the valve 61 closed until the valve is forcibly moved to an open position by swinging of the rocker arm and the operation of the cam 25 and the tappet valve actuating structure shown in detail in Figure 6. A coil spring 66 is mounted in the sleeve 64 intermediate the piston 65 and the cotter pins 67 against which the outer end of the spring 66 abuts to hold the spring in position. This structure facilitates the quick assembly and replacement of parts when desired.

A spark plug is carried by each exhaust chamber or funnel as previously stated. The mounting of each spark plug is similar to that shown with respect to the spark plug 36 which is carried by the chamber or funnel 40, shown in Figures 3, 4 and 5. The spark plug is placed just beyond the valve seat, such as the valve seat 62, as shown in Figures 3, 4 and 5, so as to ignite the charge of fuel as it is ejected outwardly beyond the valve seat when the valve 61 is opened in proper timed relation with the operation of the valve 48 and the piston of the respective cylinders such as the piston P shown in Figures 3 and 5. The spark plugs are electrically connected to the ignition wires 32, timer, etc., in the conventional manner, to fire the spark plugs for the respective exhaust chambers or funnels at properly timed intervals. The cylinders, fuel intake casings, and exhaust chambers are preferably provided with radiating ribs or fins 68 to facilitate cooling of the engine and its associated parts.

The engine is preferably mounted upon a suitable vehicle or support within the path of air passing through a suitable air passage such as the passage shown at A in dotted lines in Figure 2. The discharge ends of the exhaust chambers face rearwardly and the air from the air passage passes rearwardly over the engine and exteriorly of the exhaust chambers in a direction opposite to the direction of travel of the vehicle upon which the engine is mounted. The vehicle carrying the engine will be driven forwardly by the

explosive power of the exhaust which is discharged from the exhaust chambers.

It should be understood that all desired auxiliary equipment may be used or added to the engine for efficient operation in actual operation without departing from the spirit of the invention.

The engine operates in the same general manner as a four-cycle engine of the conventional type, but the fuel is drawn into the intake casings, then to the cylinders, then from the cylinders to the exhaust chambers or funnels where it is then ignited exteriorly of the cylinders. The valves of the intake casing and exhaust chambers are operated in proper timed relation to the other operating parts of the engine through the medium of the cam shaft 24 and the associated parts. The engine lies in a horizontal plane and the exhaust chambers all discharge rearwardly for forward driving power. The auxiliary operating motor 11 and its associated parts 13, 19, 20 and 21 all are of a conventional type and are utilized for starting purposes and efficient operation. These elements, however, may be of a minimum size and power, for the main driving power is obtained by the firing of the exhaust discharge as set forth, after starting.

The sequence of operation is as follows:

Beginning with the suction stroke, and with the piston at a point of greatest distance from the crank shaft, the exhaust valve 61 closes and the intake valve 48 opens. The exhaust valve 61 remains closed as the piston travels toward the crank shaft. As the piston reaches the end of its inward stroke, the intake valve 48 closes and while the piston travels outwardly on its compression stroke, the exhaust valve 61 still remains closed. As the piston reaches the end of its outward or compression stroke, the exhaust valve 61 opens and the intake valve 48 remains closed. As the exhaust valve 61 opens the fuel passes through the valve 61 and into the exhaust chamber, where the compressed fuel is ignited by the spark plug 36. The spark plug 36 is timed to fire just after the exhaust valve 61 opens, and while the exhaust valve 61 is open all of the fuel on either side of the valve 61 will be ignited. This action exerts a thrust upon the piston, as well as through the exhaust chamber, to keep the engine turning. As the piston travels toward the crank shaft, on the power stroke, the intake valve 48 remains closed and the exhaust valve 61 remains open. When the piston reaches the point nearest the crank shaft and returns on its exhaust stroke, the intake valve 48 remains closed. The exhaust valve 61 remains open until the piston reaches the limit of its outward stroke. At this point the exhaust valve 61 closes and the intake valve 48 opens. The operation above set forth continues in the order described.

It should be understood that certain detail changes in construction and arrangement of parts may be employed without departing from the spirit of the invention so long as such changes fall within the scope of the appended claims.

Having described the invention, what is claimed as new is:

1. In combination with a vehicle, an exhaust propulsion engine, said engine comprising a cylinder, a piston operating therein, a fuel-air mixture intake control means for supplying a fuel mixture to the cylinder at timed intervals, an exhaust chamber receiving the fuel mixture from the cylinder at timed intervals, said cylinder having a port communicating with said chamber,

said exhaust chamber having a discharge outlet extending rearwardly of the engine, a valve for opening and closing said port at timed intervals, firing means for the fuel mixture located beyond the valve, means for actuating the firing means at timed intervals for exploding the fuel adjacent the discharge outlet within the exhaust chamber in timed relation to the opening of said valve for driving said vehicle forwardly as the exhaust of the fired fuel is expelled outwardly of the discharge outlet of the exhaust chamber and rearwardly of said vehicle, said valve comprising a valve head, a sleeve, a second piston in said sleeve spaced from said valve head to balance pressure against the valve head and prevent accidental opening of the valve as fuel enters the exhaust chamber from the cylinder, a stem supporting the valve head and piston of the valve, a spring normally holding the valve in a closed position, and an actuating means engaging said valve stem for opening said valve.

2. In combination with a vehicle, an exhaust propulsion engine, said engine comprising a cylinder, a driving piston operating therein, a piston actuating means, a fuel-air mixture intake control means for supplying a fuel mixture to the cylinder at timed intervals, an exhaust chamber receiving the fuel mixture from the cylinder at timed intervals, said cylinder having a port communicating with said chamber, said exhaust chamber having a discharge outlet extending rearwardly of the engine, a valve for opening and closing said port at timed intervals, firing means for the fuel located beyond the valve, means for actuating the firing means at timed intervals for exploding the fuel adjacent the discharge outlet within the exhaust chamber at the time the fuel enters the exhaust chamber and the valve is opened for driving said vehicle forwardly as the exhaust of the fired fuel is expelled outwardly of the discharge outlet of the exhaust chamber and rearwardly of said vehicle, said valve comprising a valve head, a sleeve, a second piston in said sleeve spaced from said valve head to balance pressure against the valve head and prevent accidental opening of the valve as fuel enters the exhaust chamber from the first mentioned cylinder, a stem supporting the valve head and piston of the valve, a spring normally holding the valve in a closed position, an actuating means engaging said valve stem for opening said valve, said actuating means comprising a rocker arm engaging said valve stem, and an actuating cam and tappet means for rocking said rocker arm at timed intervals.

3. In combination with a vehicle, an exhaust propulsion engine, said engine comprising a cylinder, a piston operating therein, a piston actuating means, a fuel-air mixture, intake control means for supplying a fuel mixture to the cylinder at timed intervals, an exhaust chamber receiving the fuel mixture from the cylinder at timed intervals, said exhaust chamber having a discharge outlet extending rearwardly of the engine, a valve for opening and closing said port at timed intervals, firing means for the fuel located beyond the valve, means for actuating the firing means at timed intervals for exploding the fuel adjacent the discharge outlet within the exhaust chamber in timed relation to the opening of said valve for driving said vehicle forwardly as the exhaust of the fired fuel is expelled outwardly of the discharge outlet of the exhaust chamber and rearwardly of said vehicle, said valve comprising a valve head, a sleeve, a second piston in said sleeve spaced from said valve head to bal-

ance pressure against the valve head and prevent accidental opening of the valve as fuel enters the exhaust chamber from the first-mentioned cylinder, a stem supporting the valve head and piston of the valve, a spring normally holding the valve in a closed position, an actuating means engaging said valve stem for opening said valve, an open ended sleeve encasing said spring, and transversely extending cotter pins spanning said open ended sleeve and abutting the spring for removably retaining the spring in said sleeve.

4. In combination with an auxiliary operating motor and control means therefor, an exhaust propulsion engine having a piston actuating crank shaft connected to said motor, a plurality of cylinders, pistons operating therein and connected to said crank shaft, a fuel-air mixture intake means supplying fuel-air mixture to each of said cylinders, control means for controlling the passage of a fuel mixture from the intake means to the cylinder, cam means for actuating the control means at timed intervals, an exhaust chamber for receiving exhaust from each cylinder, each cylinder having a port communicating with an exhaust chamber, each exhaust chamber having an exhaust discharge outlet and a flared outer discharge end, a valve for opening and closing said port, cam means for actuating said last mentioned valve at timed intervals, a spark plug carried adjacent the discharge outlet of each exhaust chamber, and means to fire the exhaust fuel at timed intervals with the opening of said outlet port as it passes through the discharge outlet to produce an exhaust propulsion force.

5. In combination with a vehicle, an exhaust propulsion engine, said engine comprising a primary cylinder, a primary piston in said cylinder, means for actuating said piston, an intake casing carried by said cylinder, said intake casing having a discharge port communicating with the interior of said cylinder for supplying a fuel-air mixture to the cylinder, valve means for opening and closing said port at timed intervals relative to the movement of said piston, an exhaust funnel carried by said cylinder, said funnel having a hollow sleeve communicating with said cylinder, a second piston slidable in said sleeve, a valve stem carried by said second piston, an exhaust valve carried by said stem, said funnel having an exhaust port, said exhaust valve adapted to open and close said exhaust port of said funnel, means for actuating said valve stem in timed relation with the movement of said primary piston, said second piston being adapted to equalize the pressure in said chamber between the exhaust valve and said second piston, a spark plug carried by said funnel outwardly of said exhaust valve, and means for actuating the spark plug to ignite mixture passing outwardly of the exhaust funnel in timed relation to the opening of the exhaust valve.

6. In combination with a vehicle, an exhaust propulsion engine, said engine comprising a plurality of primary cylinders, a primary piston in each cylinder, means for actuating the piston of each cylinder, an intake casing for each cylinder, each intake casing having a discharge port communicating with the interior of a companion cylinder for supplying a fuel-air mixture to the cylinder, valve means for opening and closing each port at timed intervals relative to the movement of each piston, an exhaust funnel for each cylinder, each funnel having a flared outer end, a hollow sleeve carried by and communicating with each companion cylinder, a second balancing piston slidable in each sleeve, an exhaust valve

connected to each balancing piston, each funnel having an exhaust port, the exhaust valves adapted to open and close said exhaust ports, means for actuating said exhaust ports in timed relation to the movement of said primary pistons to control the discharge of exhaust through said funnels, a spark plug for each exhaust funnel located outwardly of each exhaust port, and means for actuating said spark plugs in timed relation to the opening of said exhaust valves. 10
